Inventor:

Peter F. Connolly.

Attys.

By

UNITED STATES PATENT OFFICE.

PETER F. CONNOLLY, OF CHICAGO, ILLINOIS.

COMBINED INSULATED STEM AND JOINT.

1,377,318.

Specification of Letters Patent.

Patented May 10, 1921.

Application filed September 13, 1920. Serial No. 409,774.

To all whom it may concern:

Be it known that I, PETER F. CONNOLLY, a citizen of the United States, residing at Chicago, Cook county, Illinois, have invented 5 certain new and useful Improvements in Combined Insulated Stems and Joints, of which the following, taken in connection with the drawings, is a description.

My invention relates to the insulated stem 10 and joint used in connection with electric fixtures and has for its object the production of a combined insulated stem and joint by means of which the wires connected with the source of electricity are carried to the lighting fixtures.

It is also an object of my invention to provide in the stem means whereby wires may be threaded therein, through the stem without the aid of other tools to engage the wire and 20 draw it through the stem as has heretofore been necessary.

A further object of my invention is to provide an insulating means between the stem and loop at the end thereof which shall be 25 simple in construction, cheap to manufacture, easy to install, and very effective for the purpose intended.

In the accompanying drawings I have illustrated what I now consider the preferred form of an embodiment of my invention, although I do not desire to be limited 30 to the size, proportion, or minor details thereof, which may be changed without departing from the spirit of my invention, and in these drawings:—

Figure 1 is a vertical, sectional view through the stem and a side elevation of the nipple, washer and loop,

Fig. 2 is a vertical, sectional view taken 40 on line 2—2 of Fig. 1,

Fig. 3 is a transverse, sectional view taken on line 3—3 of Fig. 2, looking in the direction of the arrow.

Referring to the drawings A represents 45 a tubular stem which is connected in the usual manner with the knock-out box located in the wall or ceiling of the building. Threaded in this tube near the end thereof is a plug B fitting closely in the inner wall 50 of the stem A. This plug is elongated on one side thereof on a line diagonal to the axis, and has formed therein a channel or groove b, which terminates at the opening a through the wall of the pipe A.

55 The electric light wires to be carried to the fixtures are passed through this opening

a, and guided by the channel b down through the nipple to the fixture outside, (the fixture referred to herein forming no part of my invention, it is not shown in the drawing, 60 as any lighting fixtures now on the market are suitable for the purpose.)

At the end of the stem opposite the plug B is a loop C, which has formed on one side thereof, as at c, a tubular neck portion 65 through which extends the opening c', which has open communication with the interior of the stem A.

A threaded socket D is provided in this neck portion C, the diameter of the socket 70 being larger than the opening c' thereby providing a shoulder c², which forms a seat for the end of the nipple D'. The nipple D' is exteriorly screw threaded and has engagement with the interior threads in the 75 socket D.

E is a washer formed of insulating material and surrounds the shank of the nipple D' and is positioned between the neck c of the loop C at the end of the tubular stem A. 80

The washer E is provided with an annular recess E', which receives the end of a sleeve or collar E², which fits inside of the tubular stem A and surrounds the body of the nipple D'. 85

The stem A is preferably provided with an inwardly turned flange a², upon which is seated the shoulder a³, formed on the collar E².

A flange d is formed on the end of the 90 nipple D' and seats against the insulating sleeve E². When these parts are assembled as shown in Fig. 2, a perfectly tight insulated joint is formed between the stem A and the loop C. When the electric wires are 95 introduced into the stem A, through the opening a, the channel b directs them downwardly toward the opening c³, which extends through the nipple D' and opening c'; the wiring may then be extended as desired; usually with the chains from which the fixture 100 is suspended from the loop C, and they are carried to the place desired in any well known manner.

I claim:—

1. In an insulating stem and joint, the combination of a tubular member, a plug secured in one end thereof, said plug having a channel formed therein, the end of which channel terminates at an opening through 110 the wall of the stem.

2. In an insulating stem and joint, the

combination of a tubular member, a plug secured in one end thereof, said plug being elongated on one side thereof on a line diagonal to its axis and having a channel formed therein, the end of which is coincident with an opening through the wall of the stem.

3. A new article of manufacture, comprising in combination a tubular member, a plug secured in one end thereof, said plug

having a channel formed therein, which is coincident with an opening through the wall of the tubular member, a nipple having engagement with the opposite end of said tubular member, and means for insulating said nipple from the tubular member.

In testimony whereof I have signed this specification.

PETER F. CONNOLLY.
